(57) **CLAIM**

The ornamental design of a cap mounted headlight with battery pack, as shown and described.

DESCRIPTION

FIG. 1 is a perspective view of the cap mounted headlight with battery pack of the present invention;

FIG. 2 is a front view thereof;

FIG. 3 is a side view thereof, the opposite side view being substantially the same as a mirror image thereof;

FIG. 4 is a rear view thereof;

FIG. 5 is a top view thereof, with the wire broken away in the center to indicate indeterminate length; and,

FIG. 6 is a bottom view thereof.
